UNITED STATES PATENT OFFICE.

DE VER H. WARNER, OF BRIDGEPORT, CONNECTICUT.

DESIGN FOR A CORSET.

SPECIFICATION forming part of Design No. 22,673, dated August 8, 1893.

Application filed May 2, 1893. Serial No. 472,793. Term of patent 3½ years.

To all whom it may concern:

Be it known that I, DE VER H. WARNER, a citizen of the United States, residing at Bridgeport, in the county of Fairfield and State of Connecticut, have invented a certain new and useful Design for Corsets, of which the following is a specification.

My invention relates to a design for corsets, and more particularly to a design for the bust portion of the corset, and it has for its object to produce an aesthetical effect of the corset and to render it attractive in appearance.

In the accompanying drawing I have illustrated a plan view of one half of a corset in which is embodied my design.

The essential feature of my new and original design consists in a corset ornamented with a vertical strip extending over the bust

portion thereof, and having a ribbed portion C, C, arranged on each side of the strip, extending downward at an acute angle therefrom, presenting the general appearance of an arrow-head and having acute-angled, plain fields E at the sides of the vertical strip, and below the ribbed portions C. 20 25

What I claim is—

The design for a corset, substantially as herein shown and set forth.

In testimony whereof I have signed my name to this specification in the presence of 30 two subscribing witnesses.

DE VER H. WARNER.
